PANEL FOR A CHAIR BACK

Filed April 11, 1924

Inventor:

Harold P. Nelson.

UNITED STATES PATENT OFFICE.

HAROLD P. NELSON, OF NORTH BERGEN, NEW JERSEY.

DESIGN FOR A PANEL FOR A CHAIR BACK.

Application filed April 11, 1924. Serial No. 9,232. Term of patent 3½ years.

To all whom it may concern:

Be it known that I, HAROLD P. NELSON, a citizen of the United States, residing at North Bergen, in the county of Hudson and State of New Jersey, have invented a new, original, and ornamental Design for a Panel for a Chair Back, of which the following is a specification, reference being

had to the accompanying drawing, forming part thereof.

The figure is a plan view of a chair back, showing my new design.

I claim:

The ornamental design for a panel for a chair back as shown.

HAROLD P. NELSON.
